UNITED STATES PATENT OFFICE

94,637

DESIGN FOR A SPOON OR SIMILAR ARTICLE

Gideon N. Stieff and Ellis T. Baker, Baltimore,
Md., assignors to The Stieff Company, a corporation of Maryland

Application November 30, 1934, Serial No. 54,211

Term of patent 14 years

To all whom it may concern:

Be it known that we, Gideon N. Stieff and Ellis T. Baker, citizens of the United States, residing at Baltimore, in the State of Maryland, have invented a new, original, and ornamental Design for a Spoon or Similar Article, of which the following is a specification, reference being had to the accompanying drawing, forming a part thereof, in which:

The back of the spoon shown in Figures 1 and 2 is plain.

We claim:

The ornamental design for a spoon or similar article, substantially as shown and described.

GIDEON N. STIEFF.
ELLIS T. BAKER.
